UNITED STATES PATENT OFFICE.

LULU VERHOREN LAVELL, OF MINNEAPOLIS, MINNESOTA.

DESIGN FOR A CANDLEHOLDER.

Application filed May 11, 1925. Serial No. 13,410. Term of patent 3½ years.

To all whom it may concern:

Be it known that I, LULU VERHOREN LAVELL, a citizen of the United States, residing at Minneapolis, in the county of Hennepin and State of Minnesota, have invented a new, original, and ornamental Design for Candleholders, of which the following is a specification, reference being had to the accompanying drawing, forming part thereof.

The figure is a perspective view of a candleholder showing my new design.

I claim:

The ornamental design for a candleholder as shown.

LULU VERHOREN LAVELL.
